UNITED STATES PATENT OFFICE.

ARCHIEBALD L. MCKELVEY, OF ST. LOUIS, MISSOURI.

TORPEDO OR MINE GUARD.

1,243,848.

Specification of Letters Patent. Patented Oct. 23, 1917.

Application filed November 21, 1914, Serial No. 873,388. Renewed June 7, 1917. Serial No. 173,417.

To all whom it may concern:

Be it known that I, ARCHIEBALD L. MCKELVEY, a citizen of the United States, residing at the city of St. Louis and State of Missouri, have invented a new and useful 5 Torpedo or Mine Guard, of which the following is a specification.

This invention relates to improvements in torpedo or mine guards for ships.

10 An object of the invention is to provide a guard or screen which may be readily adjusted to encompass the hull of the ship below the water line so as to prevent the impact of torpedoes or mines against the hull 15 with provision for raising the screen in sections out of the water when not in use.

Another object is to provide a guard or screen for ships, composed of a series of independently adjustable sections, with supporting and controlling devices for holding 20 the sections in proper position to form a continuous guard or shield within the water and at a suitable distance from the sides of the ship to prevent serious damage or injury as the result of the explosion of torpedoes or mines against the guard or shield, 25 suitable actuating apparatus being provided for raising and lowering the various sections, whereby the continuous guard or 30 shield may be maintained in the water, or removed from the water, according to the circumstances and requirements of the occasion.

With the foregoing and other obvious advantages to be obtained from the present invention, in view I have designed and arranged the several parts in the preferred manner illustrated in the drawings to which reference is made in the following detailed 40 disclosure of the invention. In the drawings—

Figure 1 is a side elevation of a ship equipped with a guard or shield of the present invention, shown in position, for the protection of the hull.

Fig. 2 is a transverse section more clearly illustrating the method of supporting a section of the screen in an adjustment to protect the hull.

50 Fig. 3 is a view similar to that of Fig. 5 showing a section of the screen raised.

In the embodiment of the invention illustrated in the drawings the guard or screen is shown as composed of a series of independently adjustable sections, each section comprising a rectangular frame composed

of vertical members 1 and cross members 2; the members 1 and 2 are preferably in the form of angle irons rigidly secured together at the points of intersection, and a screen 3 composed of a series of interlaced rods extending transversely and vertically, secured at their extremities in the outer members of the frame. The sections of the screen or guard thus formed are supported by the 65 hull of the ship by means of a series of lower brackets 4 and upper brackets 5, arranged at suitable intervals around the hull of the ship, said brackets pivotally supporting extending arms 6, which are pivotally secured 70 at their outer ends to said sections of the screen or guard. The brackets 5 are preferably provided with extending portions 7 which are adapted to bear against the under face of the upper series of arms 6 when said 75 arms are in horizontal adjustment and thereby assist in supporting the sections of the guard or screen.

The apparatus for raising and lowering the various sections of the guard or shield 80 comprises a series of standards 8 secured to the deck of the ship at suitable intervals, which standards have revolvably mounted therein sheaves 9 which are adapted to accommodate a series of cables 10 which are 85 secured at their outer ends to the respective arms 6 adjacent to the outer ends of said arms, said cables passing over the sheaves 9 and preferably through the deck of the ship 90 in the manner clearly illustrated in Fig. 2 of the drawing.

I prefer to provide for each section an independently operable power winch 11 adapted to reel and unreel one of the cables of each section, the remaining cables being 95 weighted by counterweights 12 so that the sections may be raised and lowered with facility and with a minimum amount of power.

In addition to the support furnished by the extending portions of the bracket 7 and the cables with their supporting standards 8, the several sections are further provided with supporting means in the form of flexible cables or chains 13 secured at one end to the hull of the ship and at the other end to the frame of the guard or shield sections.

The several sections of the guard or shield are disposed substantially as shown in the drawings, so that the hull of the ship, when the shield is in position for protecting the same, is completely enveloped thereby, the screen extending for a considerable distance

downwardly below the keel of the ship and extending upwardly slightly above the water line, the two forward sections meeting in front of the prow of the ship. It is contemplated that the length of the arms 5 when in the adjustment shown in Fig. 2 will be such as to support the sections of the guard or shield at a sufficient distance from the hull of the ship to prevent torpedoes or 10 floating or anchored mines from approaching sufficiently near the ship to cause any serious injury or damage. The torpedoes or mines impacting against the shield will be exploded, and while it is understood that in 15 ordinary use the section against which the torpedo or mine may strike will be damaged, nevertheless repairs can readily be effected without exposing a large portion of the ship, as each section is independent of the others. 20 When the shield or guard is not in use it is raised by means of the power apparatus, inwardly near the hull of the ship as shown in Fig. 3 of the drawings. When in this adjustment it will afford little or no resistance 25 to the progress of the ship through the water when in motion.

I claim:

1. A mine or torpedo guard for ships, comprising a series of independently adjustable sections, each section being composed of a rigid metal frame and interlaced rods extending vertically and horizontally and supported by said frame, in combination with means for adjustably supporting said sections comprising for each section a plurality of spaced brackets arranged in a rectangular series, arms pivoted to said brackets and extending outwardly and pivoted to said frames, horizontal extensions on the upper ones of said brackets adapted to constitute a support for the upper ones of said arms, standards supported on the deck of the ship, sheaves revolvably mounted in said standards, flexible connections passing over said sheaves and having their outer ends connected to the outer end of the upper ones of said arms, respectively, and mechanism for winding and unwinding said flexible connections, substantially as specified.
- 50 2. A mine or torpedo guard for ships, comprising a series of independently adjustable sections, each section being composed of a metal screen, in combination with means for adjustably supporting said sections, comprising for each section a plurality of spaced brackets arranged in a rectangular series, arms pivoted to said brackets and extending outwardly and pivoted to said screens, extensions on the upper ones 55 of said brackets constituting supports for

the upper ones of said arms when in one adjustment, and mechanism for raising and lowering said sections, substantially as specified.

3. A mine or torpedo guard for ships comprising a plurality of brackets secured to the side of the ship in a rectangular series, outwardly extending arms pivoted to said brackets, a screen vertically disposed and having pivot connections with said arms, 65 a series of horizontal rests formed integral with selected ones of said brackets adapted to support certain ones of said arms when the screen is in one adjustment and mechanism for raising and lowering said arms 70 and thereby said screen, substantially as specified.

4. A mine or torpedo guard for ships comprising a plurality of independently adjustable sections, each section being composed 80 of a rigid metal frame and interlaced rods supported thereby, in combination with means for adjustably supporting said sections comprising for each section a plurality of brackets secured to the ship's sides and 85 arranged in rectangular series, arms pivoted to said brackets and extending outwardly from the ship and having pivot connections with said frames, extensions from certain of said brackets adapted to constitute a support for certain of said arms, and power mechanism arranged to raise and lower said sections, substantially as specified.

5. A mine or torpedo guard for ships, comprising a plurality of rigid screens, 95 brackets secured to the side of the ship, arms pivoted to said brackets and to said screens, supports for said arms located adjacent to selected ones of said brackets for supporting the screens in one position, and 100 mechanism for raising and lowering said screens.

6. A mine or torpedo guard for ships, comprising a plurality of brackets supported by the side of the ship, outwardly 105 extending arms pivoted to each of said brackets, a rigid screen having pivot connections with said arms, a series of horizontal rests adjacent to selected ones of said brackets adapted to support certain ones of said arms when the screen is in one adjustment, and mechanism for raising and lowering said screen.

In witness whereof, I have signed this specification in the presence of two subscribing witnesses.

ARCHIEBALD L. MCKELVEY.
